UNITED STATES PATENT OFFICE.

ALFRED SMALLWOOD, OF LONDON, ENGLAND.

FURNACE.

1,290,385.

Specification of Letters Patent.

Patented Jan. 7, 1919.

Application filed May 9, 1917. Serial No. 167,547.

To all whom it may concern:

Be it known that I, ALFRED SMALLWOOD, a subject of the Kingdom of Great Britain, residing at 42 Hargrave Park, Highgate, 5 London, N., in the county of Middlesex, England, have invented certain new and useful Improvements in or Relating to Furnaces, of which the following is a specification.

This invention comprises certain improvements in or relating to furnaces, and is particularly applicable to furnaces for the heating of billets, or other articles of a like character. The present invention provides a particularly simple and efficient mode of and 10 means for displacing or advancing the billets within the heating chamber so that they may be introduced at one extremity, caused to traverse the length of the heating chamber, and removed from the other extremity. 15 The present invention relates to mechanism for displacing or advancing articles within a heating chamber, of the type in which the articles are advanced or displaced upon supporting means adapted to elevate 20 and lower the goods, and also to displace or advance the goods horizontally, and in which the mechanism for elevating and lowering said supporting means also effects the horizontal displacement of the supporting means 25 in an action according to which said supporting means are raised by said elevating and lowering mechanism, then advanced or displaced horizontally by the same mechanism, and then still by the same mechanism 30 lowered in their displaced or advanced condition. According to the present invention, in this type of mechanism the supporting means are adapted to be lowered into openings adapted to contain cooling liquid, and 35 when the bars are in their lowered positions they are thereby protected from the heat of the furnace chamber. The said supporting means may furthermore be adapted to be cooled internally, for which purpose they 40 are hollow and adapted to have cooling liquid circulated through them.

In order that this invention may be clearly understood and readily carried into practice, reference may be had to the appended explanatory two sheets of drawings, upon which:—

Figure 1 is a sectional plan of a furnace according to the present invention.

Fig. 2 is an enlarged sectional end elevation of the furnace shown in Fig. 1. 55

Fig. 3 illustrates in side elevation a detail in the furnace shown in Fig. 1.

In the drawings, *a* is the furnace chamber in which the goods are heated, and to which furnace gases from solid, liquid, or gaseous fuel fittings are supplied by any suitable arrangements (not shown). The furnace chamber *a* has longitudinal openings *b* in its base; these openings *b* are adapted to accommodate the bars *c* by which the billets *d* or other goods are displaced. The bars *c* extend beyond the extremities of the furnace chamber at both ends so that the goods can be placed upon them at one extremity of the furnace outside of the heating chamber 70 thereof, and removed therefrom at the other end of the furnace outside of the heating chamber thereof. At positions at or near to their ends, conveniently in the vicinities of the ends of the furnace chamber, said bars *c* 75 are furnished with eccentric straps *e*. These eccentric straps are bolted or otherwise secured to the bars, and they are adapted to coöperate with eccentrics *f* mounted upon transverse shafts *g*, one of which is provided at each extremity of the furnace. Each transverse shaft *g* carries two eccentrics *f*, one for each bar, and the said transverse shafts *g* also each carry a central worm wheel *h* which meshes with a worm provided 80 upon a vertical shaft *i*, which last-mentioned shaft *i* carries a bevel wheel *j*. This bevel wheel *j* meshes with a bevel wheel *k* mounted on a laterally extending shaft *l*. The laterally extending shafts *l*, one at each end of 90 the furnace, carry at their outer extremities other bevel wheels *m* which are in mesh with bevel wheels *n* provided upon a common longitudinal shaft *o* which is adapted to be driven in any suitable manner. In the arrangement illustrated, the shaft *o* carries fast and loose pulleys *p* to which the drive is imparted by belt gearing. 95

The bars *c* are conveniently hollow and adapted to have water or other cooling liquid circulated through them. For this purpose they may each comprise a channel-shaped part and a closure plate *q* adapted to form conduits *w* in which the water is adapted to circulate, as for instance by flexible supply and egress conduits (not shown) 100

provided in connection with each end of each bar.

The openings *b* which extend the length of the furnace communicate below the base of the furnace chamber with longitudinal chambers *r*. These chambers are adapted to contain water or other cooling liquid, and when the bars are in their lowered positions they are thereby immersed in the water and protected from the heat of the furnace chamber. Closure members *s* may be incorporated and adapted to isolate the chambers *r* from recesses *b* in which the bars *c* are adapted to operate when displacing the goods.

Vertical sliding doors *t* are provided at the extremities of the furnace chamber.

u, *u* are base extensions provided one at each end of the furnace chamber, throughout the length of which base extensions the bars *c* extend, and said base extensions have their upper surfaces at a level coinciding with that of the base of the furnace chamber.

In operation the goods are placed upon one of the base extensions *u*. The corresponding door *t* is raised, and the shaft *o* is driven continuously so that by virtue of the eccentrics *f*, the bars *c* are elevated to lift the goods above the base upon which they rest. The goods are then moved forward by the further action of the eccentrics until the bars again descend below the upper surface of the base, at which point the goods are replaced upon the base in an advanced position. By this process the goods may be intermittently and progressively advanced as desired until they acquire the desired position within the furnace chamber. In

like manner the goods may be removed from the furnace chamber on to the base extension at the other end of the furnace.

What I claim as my invention and desire to secure by Letters Patent is:—

1. A furnace for heating billets or the like, including a furnace floor provided with longitudinal grooves constituting water baths at the lower portion, bars normally disposed in said baths, and means for lifting the bars in parallel motion from the baths and above said floor to raise the work and move the same forward a predetermined distance and then replace the work on the floor and return the bars to the baths.

2. In a furnace for heating billets and the like, a furnace floor provided with base extensions in the same horizontal plane, said base extensions being located outside the furnace proper, said floor and extensions being provided with longitudinal grooves constituting water baths at the lower portion, bars normally disposed in said baths, and means for lifting said bars in parallel motion from the baths and above said floor to raise the work above one of said extensions and move the same forward to convey the work in a series of steps through the furnace onto the opposite base extension, said means returning the bars between successive steps to the baths.

In testimony whereof I affix my signature in presence of two witnesses.

ALFRED SMALLWOOD.
